UNITED STATES PATENT OFFICE

126,897

DESIGN FOR A REAR FENDER FOR A VEHICLE

Ronald J. Waterbury, Birmingham, Mich., as-
signor to General Motors Corporation, Detroit,
Mich., a corporation of Delaware

Application May 28, 1940, Serial No. 92,668

Term of patent 7 years

To all whom it may concern:

Be it known that I, Ronald J. Waterbury, a citizen of the United States and a resident of Birmingham, county of Oakland and State of Michigan, have invented a new, original, and ornamental Design for a Rear Fender for a Vehicle, of which the following is a specification, reference being made to the accompanying drawing, forming a part thereof, in which

Figure 1 is a plan view of a rear fender for a vehicle showing my new design.

Figure 2 is a side elevational view of the fender.

Figures 3, 4, and 5 are enlarged sections on the corresponding lines of Figure 2.

I claim:

The ornamental design for a rear fender for a vehicle, as shown.

RONALD J. WATERBURY.
